CLAIM

The ornamental design for a toner cartridge, as shown and described.

DESCRIPTION

FIG. 1 is a front, top, and right side perspective view of a toner cartridge;

FIG. 2 is a rear, bottom, and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the figures illustrate portions of the toner cartridge that form no part of the claimed design. In addition, the unshaded surfaces that directly adjoin the claimed solid line edges form no part of the claimed design.

1 Claim, 8 Drawing Sheets
